UNITED STATES PATENT OFFICE.

LEO EHRLICH, OF ST. LOUIS, MISSOURI, ASSIGNOR TO THE AMERICAN ROLL PAPER COMPANY, OF SAME PLACE.

PAPER-CUTTER.

SPECIFICATION forming part of Letters Patent No. 392,857, dated November 13, 1883.

Application filed February 13, 1883. Serial No. 203,797. (No model.)

To all whom it may concern:

Be it known that I, LEO EHRLICH, of the city of St. Louis, in the State of Missouri, have invented a certain new and useful Improvement in Paper-Cutters, of which the following is a full, clear, and exact description, reference being had to the accompanying drawings, forming part of this specification, and in which—

10 Figure I is an elevation of my improved paper-cutter. Fig. II is an end view.

My invention relates to an improvement in machines for holding and cutting wrapping-paper; and my invention consists in features 15 of novelty hereinafter fully described, and pointed out in the claims.

Referring to the drawings, 1 represents a base, and 2 ends secured to and extending upward from the base. The ends are provided 20 with extensions 3, to which a knife, 4, is secured.

5 represents arms pivoted to the extensions at 6 and held in an inclined position by springs 7. I prefer to use springs composed of a single leaf, each secured to the ends, as shown at 8.

The springs act to hold the arms in a position inclined upwardly from the knife, and upon these arms the journals or gudgeons 9 of the roller 10, upon which the paper 11 is wound, bear. 30 It will thus be seen that as the springs hold the arms in an inclined position the roller will move downwardly on the latter as the paper is removed, and thus be automatically fed to the knife. As the paper is removed and the roller 35 moves toward the knife, it approaches the pivots of the arms 5, and as it does so the weight on the springs of course decreases, and the arms are made by the springs to incline more

or are given a steeper pitch to provide for the decrease in the weight of the roller against the 40 knife. Thus a uniform pressure is had between the rollers and knife at all times.

12 represents projections over the journals 9, which hold the journals on the arms 5. These are preferably formed in one part with 45 the arms. The outer ends of the arms are preferably turned up or hooked, as shown at 13, Fig. II, to avoid danger of the roller being displaced.

I claim as my invention—

1. In a paper-cutter, the combination of the roller, support for the roller, arms pivoted to the support, knife, and springs holding the arms in an inclined position, substantially as and for the purpose set forth.

2. In a paper-cutter, the combination of the base, ends secured to the base, extensions on the ends, knife secured to the extensions, arms pivoted to the extensions, springs secured to the ends and supporting the arms in an inclined position, and a roller resting on the arms, substantially as and for the purpose set forth.

3. In a paper-cutter, the combination of the base, ends secured to the base, extensions on the ends, knife secured to the extensions, arms pivoted to the extensions and having hooks on their outer ends, and projections 12 on the arms, springs secured to the ends and sustaining the arms in an inclined position, and a 70 roller bearing on the arms, substantially as and for the purpose set forth.

LEO EHRLICH.

In presence of—
EDWD. S. KNIGHT,
JOS. WAHLE.
